UNITED STATES PATENT OFFICE.

JAMES D. LYTTLE, OF FENN, AND SOLOMON CLARK, OF GRANGEVILLE, IDAHO.

COMBINED ROAD GRADING AND LEVELING MACHINE.

1,393,385.

Specification of Letters Patent. Patented Oct. 11, 1921.

Application filed January 19, 1920. Serial No. 352,605.

To all whom it may concern:

Be it known that we, JAMES D. LYTTLE and SOLOMON CLARK, citizens of the United States, and residents, respectively, of Fenn, in the county of Idaho, and Grangeville, in said county, State of Idaho, have invented new and useful Improvements in Combined Road Grading and Leveling Machines, of which the following is a specification.

10 This invention relates to and has for a main object the provision of a simplified form of road grading and leveling machine capable of being adjusted according to the requirements of the work to be done and to 15 the topography of the ground over which it is to be drawn.

Another object is to provide in a machine of the character stated runners for supporting the grading and leveling elements for 20 operation for independently mounting and adjusting said elements on said runners to such an extent as may be desired or required.

A further object is to provide main and auxiliary runners for mounting the grading 25 and leveling elements relatively adjustable for tilting one or the other side of the machine in the grading and leveling operation so as to discharge the dirt smoothly and evenly over the surface of the ground.

30 Still another object is to provide independently operable and adjustable grading and leveling elements mounted between the carrying runners of the machine, said elements being capable of adjustment to acute 35 angles relative to said runners for facilitating the cutting of the earth and the operation of the machine to a maximum advantage. Other objects will appear as the description progresses.

40 We have illustrated the principle and shown one practical embodiment of our invention in the accompanying drawings, forming a part of this invention, to which reference is had; similar characters of reference being employed throughout the specification hereinafter following and in the several views of the drawings for indicating the same and like parts.

In said drawings:

50 Figure 1 is a side elevation of our assembled machine;

Fig. 2 is a plan of the same;

Fig. 3 is a front end elevation of the same;

Fig. 4 is a rear elevation of the same;

Fig. 5 is a fragmentary plan showing the 55 adjustable leveling means;

Fig. 6 is a fragmentary sectional elevation at the rear end of the machine showing the means for adjusting the auxiliary runners;

Figs. 7, 8 and 9, are details of the hinge 60 connections between the grading and leveling means.

Our machine includes a pair of like side runners 1 and 2 with metal strips 3, 3, on the bottom thereof for preventing the wear 65 of the runners, and a plurality of transverse members 4, 5, 6 and 7 attached to the upper edges of said runners at their ends, and a pair of like auxiliary runners 8 and 9 pivotally attached at 10 and 11 to the rear ends 70 of the runners 1 and 2, respectively, and extending substantially rearwardly thereof, the lower and rear portions of said auxiliary runners being slightly tapered, as shown.

A transverse shaft 12 is journaled in the 75 rear ends of longitudinal members 13 and 14 attached to the upper sides of members 4, 5 and 6, and a lever 15 carried thereon is pivotally attached to an arm 16 carried on the front end of the runner 8. The inner 80 end of shaft 12 carries a hand lever 17, by means of which the inner ends of runners 1 and 2 may be elevated as indicated in broken lines in Fig. 1. A quadrant 18 is attached to the member 14 of the frame and has 85 notches therein adapted to be engaged by a latch 19 on lever 17 for locking said lever and said runners in any desired positions within the range of their adjustment.

Alined with shaft 12 is a similar but 90 longer shaft 20, carried in the rear ends of members 21 and 22 of the frame and said shaft is pivotally connected with runner 9 by means of a lever 23 thereon connected with an arm 24 on said runner, the inner 95 end of shaft 20 having a hand lever 25 thereon opposite lever 17 and which may be operated together with or independently of lever 17, as occasion may demand. If operated together with lever 17, the lever 25 100 may be moved therewith by means of a ring 25, as shown in Fig. 3, which may be slipped downwardly over the upper ends of both levers.

Near the rear end of the machine we 105 provide combined leveling and deflecting elements composed of members 26 and 27, which are adapted to be removably attached

to the inner sides of the main runners 1 and 2, as shown clearly in Fig. 5. When used as a leveler, member 26 is adapted to be disposed transversely of the machine and attached at its ends to hinge members 27' and 28, respectively, by means of a bolt, or the like, extending through said hinge members and interlocking members on the ends of member 26, as at 29, shown in Fig. 7. 10 It will be observed the member 27 is substantially shorter than member 26 and adapted to be hingedly connected thereto by means of the member 31 on the end of member 27. The outer end of member 27 is 15 similarly connected to the inner side of runner 2 by means of members 32 and 33. Members 26 and 27 are held in alinement diagonally of the machine between the runners 1 and 2 by means of a brace rod 34, 20 having its ends bent downwardly and inserted in the hinge members 29 and 31 and in the member 27 on runner 2. When used as a leveler, the member 27 is adapted to be removed altogether and the free end of member 26 connected as described with runner 2, as shown in full lines.

At the front end of the machine, we provide a grading element 35 having a metal cutting blade 36 on the front side thereof. 30 Said grading means is adapted to float between the runners 1 and 2 and a draft connection is provided therefor by means of a chain 37 which extends transversely of the machine and through eye bolts or eye bars 35 38, 38, attached to the front ends of the runners 1 and 2 and adapted to be connected with the grading element by means of rods 39 and 40 near opposite ends of member 35. Said rods may have hooks on their forward 40 ends for connection with the chain 37 and their rear ends are bent downwardly through sockets 41 on members 41' attached to the rear side of member 35. Thus, the bent portion of said rods will serve to hold 45 the member 35 vertically positioned at all times and the chain 37 with which said rods are connected may also serve as a main draft chain to which a team of horses may be hitched for moving the machine over the 50 surface of the ground to be graded or leveled. The angle of the grading element may be adjusted more evenly and to better advantage by the use of a chain, as at 37, than otherwise and longer rods may be used for 55 connection with the chain when it is desired to position the member 35 transversely, or nearly so, of the machine, as shown in broken lines in Fig. 2.

The depth of the cut to be made by the 60 member 35 is adapted to be regulated by foot pressure by means of a pair of parallel bars 42 and 43 attached pivotally to the upper side of said member, connected together at their rear ends by means of a transverse 65 member 44 and having a fulcrum on the

edge of transverse member 6 of the machine frame. When the operating angle of member 35 is established, the member 44 is held at right angles to the runners 1 and 2 by adjusting the ends of said member to the 70 members 42 and 43, a plurality of bolt holes 45 being provided for this purpose, and it will be obvious that when the rear ends of members 42, 43 are depressed by foot pressure on member 44, the member 35 will be 75 correspondingly elevated.

Member 35 may be depressed with sufficient pressure and effort by means of a lever 46 resting upon the upper edge thereof at a point intermediate its ends and having its 80 front end hinged at 47 to front member 7 of the frame and its rear end extending rearwardly over member 6. Thus the depression of lever 46 will depress and regulate the 85 depth of the cut made by member 35.

Now, in operation, as the machine is moved over the surface of a road, for instance with the grading element 35 in the position shown in Fig. 2, in full lines, the 90 runners 1 and 8 will be elevated as shown in broken lines in Fig. 1 and the earth cut by member 35 will be deflected by member 26 and discharged from between the runners 1 and 2 toward the inside of the road 95 for filling the depressions and making the surface of the road uniform, the runners 1 and 2 and members 4, 5 and 6 being suitably connected by means of angle plates for this purpose. The dirt so removed may be either 100 discharged toward the center or toward the side of the road, as desired, depending upon the requirements and the direction in which the machine is moved. Usually only one 105 side of the machine will be elevated at one operation, but when it is desired both sides 110 may be similarly elevated to a like extent by means of levers 17 and 23.

Our machine may be also used as a field 110 leveler or grader with equal results. As a leveler for field use only, the member 35 may be removed and the member 26 used in the position shown in full lines in Fig. 5, where a rigidly held leveling member will suffice. But in the event such will not suffice, then the same results may be accomplished with the floating leveler 35 held in the position shown in broken lines in Fig. 2. In the latter case it will be desirable to elevate both pairs of runners, so that the dirt 115 will be discharged at both sides of the machine. It will be also understood that the machine will serve as a drag and stones and the like will be also removed from the road or field thereby with satisfactory results.

It will be understood that we have shown 125 only one preferred form of structure and details of our machine, and we do not desire to limit ourselves to any specific structure or form of device, for we may substantially modify the same without departing from 130

the spirit or enlarging the scope of our invention, except as we may be limited by the appended claims.

What we claim is:

- 5 1. A grading and leveling machine having parallel supporting runners, transverse members hingedly connected thereto, and auxiliary runners extended from the rear ends of, and hingedly connected to, said supporting runners, and manually operable means connected with the inner ends of said auxiliary members, whereby said auxiliary members may be tilted, for the purpose described.
- 10 10. A grading and leveling machine having main supporting runners, straight auxiliary runners pivoted to, and extended from, the rear ends of said supporting runners, a frame for connecting said supporting runners, and manually controlled means mounted on said auxiliary runners for elevating the inner ends of said auxiliary runners, for the purpose described.
- 15 15. A grading and leveling machine comprising a pair of hingedly connected runners, and normally aligned runners on each side of the machine for contact with the ground, a frame connecting the forward runners, a combined leveler and deflector supported by the said runners, and detachably connected at its ends thereto, said member having a major and minor portion adapted to be supported in alinement, and in a diagonal plane for use as a deflector, said minor portion being capable of removal from the major portion, and said major portion being attached transversely of the runners in such case, for providing a leveler.
- 20 20. A grading and leveling machine comprising a stationary leveling element and a floating grading element forward of said leveling element, both of said elements being adjustable as to their operating angles relative to the longitudinal axis of the machine and means for supporting said leading element transversely and diagonally relative to the machine for different uses.
- 25 25. A grading and leveling machine comprising a frame, having runners thereon for contact with the ground, a member supported on said runners in a diagonal plane, for providing a deflector and capable of attachment in a transverse plane for providing a leveler, detachable means for supporting said deflector and leveler in diagonal and transverse planes, and a floating level-

ing and grading element forward of said leveling and deflecting element adjustably supported on said frame between said runners, for the purpose described.

6. A grading and leveling machine having side runners with pivoted extensions thereon, a pair of independently adjustable leveling and grading elements mounted therebetween, means for regulating the cutting depth of one of said elements, and means for discharging the dirt from beneath said runners at the rear.

7. A grading and leveling machine having side runners arranged for and capable of being elevated at their rear ends for discharging the dirt, rearwardly extended auxiliary runners hinged thereon, a stationary member diagonally disposed between said runners at the rear end and capable of adjustment to a relatively transverse position for deflecting the dirt from between said runners, and an adjustable grading member forward of said deflecting member, as set forth.

8. A grading and leveling machine including a frame having side runners thereon, a floating grading member, adjustably supported in the front of said frame, rearwardly extending bars attached to said member and overlying said frame, whereby said bars may be depressed at their rear ends for elevating said member at will, for the purpose described.

9. A grading and leveling machine comprising side runners for supporting the grading mechanism, auxiliary runners pivotally connected at the rear thereof for elevating the rear ends of said supporting runners, a combined leveler and deflector stationarily held at the rear end of the machine, a combined grader and leveler supported solely upon the ground to be graded and having a common draft connection with the grading machine and adjustable for regulating the depth of the cut to be made thereby, and further operated bars having a fulcrum on the frame and adapted to regulate the cutting depth thereof.
